UNITED STATES PATENT OFFICE.

THOMAS FLINTOFF, OF CLAREMONT, PERTH, WESTERN AUSTRALIA, AUSTRALIA.

ARTIFICIAL TOOTH.

1,390,353.

Specification of Letters Patent. Patented Sept. 13, 1921.

Application filed September 12, 1918. Serial No. 253,707.

To all whom it may concern:

Be it known that I, THOMAS FLINTOFF, a subject of the King of the United Kingdom of Great Britain and Ireland and the British 5 Dominions Overseas, and resident of Davis Road, Claremont, Perth, Western Australia, Commonwealth of Australia, have invented new and useful Improvements in or Relating to Artificial Teeth, of which the following is a specification.

This invention relates to the manufacture of artificial teeth and more particularly those designed for attachment to vulcanite and equivalent dental plates by metal keys 15 or devices connected to said teeth by dovetail or equivalent grooves, and embedded or to be embedded in the substance of the plates, the said dovetail connection admitting of relative adjustment between the keys 20 and teeth to enable the "bite" to be readily and conveniently regulated during the manufacture of the dentures.

It has heretofore been proposed that the above-named metal keys or devices (which, 25 for convenience are hereinafter referred to only as keys) be made of sheet metal bent into channel form to fit the dovetail grooves, and be provided with fingers adapted to be embedded in the material of which the plates 30 are made, and with other fingers adapted to engage with lateral recesses in the teeth with sufficient play to admit of the before-mentioned relative adjustment between keys and teeth.

35 For convenience of description it is herein assumed that the material of which the plates are composed, is vulcanite, but it is to be understood that the invention is equally applicable to dental plates formed of materials equivalent to vulcanite, such as celluloid, and to such dental plates as are formed partly or mainly of metal to which the teeth are attached or to be attached by vulcanite or its equivalent; for that reason 40 it is to be understood that wherever in this specification the word "vulcanite" occurs 45 and the context admits of it, that word is to be read as including vulcanite as well as its equivalents.

50 The before particularized construction would involve the bending of the fingers by the dentist, preparatory to the attachment of the teeth to the then plastic vulcanite, and this would absorb considerable time and call 55 for considerable care inasmuch as such bending might possibly result in chipping or

breaking of the teeth. Moreover, the manufacture of these teeth would not give entirely satisfactory results from a commercial point of view owing to it involving the necessity of supplying the keys of different lengths to suit the various types or classes of teeth to be fitted.

The present invention aims at overcoming the foregoing difficulties by providing a 65 metal key structure in a form which readily admits of its being cut into lengths suitable to the particular requirements of the respective teeth.

The invention will now be described by 70 reference to the accompanying drawings in which:—

Figure 1 is a vertical section of a portion of a denture fitted with one of the improved teeth;

Fig. 2 is a rear elevation of the tooth shown in Fig. 1, detached from the plate;

Figs. 3 and 4 are horizontal sections taken respectively on the lines 3—3 and 4—4 of Fig. 2, and

Figs. 5 and 6 are perspective views respectively showing two different forms of the before-mentioned key structure.

Like reference letters are used to indicate the same parts in all figures of the drawings.

Each tooth *a* according to the present invention, is formed with a dovetail or equivalent groove *b* which does not extend to the biting edge *c*. Preferably the groove *b* is open at the end directed toward the non-biting edge and closed at the opposite end; it is, however, to be understood that the invention is not limited to the arrangement of groove represented in the drawings as that groove may be open at either end or, indeed, at both ends if desired.

The dovetail groove *b*, at its widest part, is of such width as to accommodate the flat part or back *d* of a key with sufficient looseness to admit of the said key being freely 100 moved longitudinally within the groove, in which latter the key is retained by the inwardly extending edges of the said groove, as shown best in Figs. 3 and 4.

Each key comprises, besides a back *d*, as 105 just described, a plurality of pins or studs *d*¹, by which the respective tooth becomes anchored to the dental plate; that represented in Figs. 1, 2 and 3 has two such studs which, in the arrangement illustrated, are 110 abreast of each other. The studs *d*¹ are rigidly attached to (as by hard soldering)

or integral with the back, and the keys complete may be cut by the dentist or consumer from strips supplied in the form illustrated in Fig. 5 or Fig. 6. In the arrangement 5 shown in Fig. 5, the studs d^1 are provided in pairs extending transversely of the back d , and the keys are formed by cutting the back transversely between adjacent pairs of studs 10 the dimensions of the severed portion of the back being preferably such as will admit of that portion being inserted in the groove b with the studs either abreast of each other as shown in Fig. 2, or one above the other, according to the particular requirements of 15 the respective tooth.

In the arrangement shown in Fig. 6, the studs d^1 are provided in pairs alined all in a single row, and the individual keys may be formed by cutting the back d trans- 20 versely between adjacent pairs.

It will be found most convenient to have the back d of a width suitable for sliding freely into the groove b , and to have the studs d^1 so located thereon that each severed 25 portion will have a pair or plurality of such studs and will be capable of being slipped into the groove b with any of its edges foremost so that the studs thereon may be alined either transversely or longi- 30 tudinally of the groove. The present invention however also includes the provision of a metal key structure in sheet form that is to say a form which, for separation into independent keys, would involve cutting in 35 two directions at an angle to each other, and it is to be understood that the following claims are intended to cover that particular structure. In all cases, the dimensions of the back d of each independent key 40 must be such that the back may be moved longitudinally within the groove b without either protruding through the open end or contacting with the closed end of the groove.

By reference more particularly to Figs. 45 2 and 4, it will be seen that the tooth α is formed with two lateral recesses e , branching out from the dovetail groove b , as has heretofore been proposed for the purpose of receiving part of the vulcanite f , Fig. 1, and 50 thereby affording increased anchorage between the said tooth and vulcanite. By further reference to figure 1, it will be seen that the two studs d^1 are completely embedded

in the vulcanite f which also penetrates into the groove b so as to completely fill those 55 parts of the latter which are not occupied by the back d .

Having described my invention, I declare that what I claim and desire to secure by Letters Patent is:—

1. The combination with an artificial tooth having a groove of dovetail cross section extending longitudinally therein and having an open end directed toward the non-biting edge of the tooth, of a flat metal 65 back adapted to be slid within the dovetail groove and on which the tooth is adjustable to regulate the bite, and studs rigid on the metal back extending outward from the groove, the length of the groove being 70 greater than the measurement in the same direction of the metal back so that regulation of the bite can be effected by adjusting the tooth relatively to the back without the latter being caused to protrude through the 75 open end or to contact with the closed end of the groove.

2. The combination with an artificial tooth having a groove extending longitudinally therein and opening at one end toward the non-biting edge of the tooth, of recesses 80 branching laterally from the groove, intermediate the ends of the latter, a flat metal back engaging with the dovetail groove, the tooth and metal back being relatively mov- 85 able to regulate the bite without disengaging the groove and back, and studs rigid on the back extending outward from the groove.

3. As a new article of manufacture for 90 use in the production of artificial teeth, a flat sheet metal back plane on one side and on the other side having a plurality of anchoring studs rigid thereon, the said back being adapted to be cut into a plurality of 95 individual keys each comprising a flat back adapted to fit within a groove in a tooth and a plurality of the said studs projecting from the back at points intermediate the edges thereof and adapted to be embedded 100 in the material of which a dental plate is composed.

In testimony whereof I have affixed my signature.

THOMAS FLINTOFF.
